P. J. H. MOORE.
OZONIZING APPARATUS.

APPLICATION FILED JUNE 19, 1917. RENEWED JUNE 30, 1919.

By Joshua R. Tolles
his Attorney.

UNITED STATES PATENT OFFICE.

PAYTON J. H. MOORE, OF CHICAGO, ILLINOIS, ASSIGNOR TO AMERICAN GRAIN DEODORIZING CO., OF CHICAGO, ILLINOIS, A CORPORATION OF ILLINOIS.

OZONIZING APPARATUS.

1,326,952.

Specification of Letters Patent.

Patented Jan. 6, 1920.

Original application filed March 1, 1917, Serial No. 151,753. Divided and this application filed June 19, 1917, Serial No. 175,597. Renewed June 30, 1919. Serial No. 307,783.

To all whom it may concern:

Be it known that I, PAYTON J. H. MOORE, a citizen of the United States, and a resident of the city of Chicago, county of Cook, and 5 State of Illinois, have invented certain new and useful Improvements in Ozonizing Apparatus, of which the following is a specification.

My invention relates to improvements in 10 ozonizing apparatus, the object of my invention being to provide an improved apparatus of this character which is of simple construction and efficient in operation, the present application being a division of my prior 15 application for treating grain, filed March 1, 1917, Serial No. 151,753.

The invention consists in the combinations and arrangements of parts hereinafter described and claimed.

20 The invention will be best understood by reference to the accompanying drawing, forming a part of this specification, and in which,

Figure 1 is a longitudinal section taken 25 through apparatus embodying my invention,

Fig. 2, a top plan view corresponding with Fig. 1, and

Fig. 3, a transverse section of the same.

30 The preferred form of construction as illustrated in the drawings comprises a suitable chamber 13 having a pipe 12 leading therefrom to carry away the ozone formed therein. The chamber 13 is divided into 35 three separate compartments, each provided with a glass top 13' and a side door 14 for access thereto. An ordinary centrifugal blower 15 is connected with chamber 13 and is adapted and arranged to force a blast of 40 air through said chamber and into the pipe 12. Arranged in each of the compartments 13 is a readily removable rectangular frame 16 having suitable electrodes 17 and 18 arranged therein. Each of the frames 16 is 45 provided with four notched cross bars 19 in which glass plates 20 and 21 are removably mounted. Grooved cross-bars 19' and 20' are arranged, as shown, in position to receive the laterally protruding edges of cross bars 50 19 in the frames 16, and the doors 14 are made of ample size to permit of the ready sliding of frames 16 therethrough. The glass plates 20 are in substantially I-form and

have electric coils 22 wound thereon, the ends of said coils being connected with electrodes 17 and 18 which are supplied with alternating currents of electricity of high potential through an ordinary transformer 23 and controller or resistance 24, as indicated. The plates 21 are interposed between adjacent plates 20 to constitute insulating barriers between the coils 22, so that the current of high potential passing through said coils produces a silent or diffused discharge which ozonizes the air passing through the chamber 13. This ozonized air passes thence through the pipe 12 into any suitable or desirable apparatus for using the same.

The apparatus set forth is a simple and efficient one for the purpose.

70 While I have illustrated and described the preferred form of construction for carrying my invention into effect, this is capable of variation and modification without departing from the spirit of the invention. 75 I, therefore, do not wish to be limited to the precise details of construction set forth, but desire to avail myself of such variations and modifications as come within the scope of the appended claims.

Having described my invention what I claim as new and desire to secure by Letters Patent is:

1. Ozonizing apparatus comprising a chamber having a transparent top; a door giving access to the side of said chamber; a frame in said chamber removable through said door; grooved supporting bars in said chamber, said frame sliding in the grooves in said bars; a plurality of coils mounted in 85 said frame; means for passing an electric current of high potential through said coils; and means for passing air through said chamber, substantially as described.

2. Ozonizing apparatus comprising a 90 chamber divided into a plurality of separate sections, each of said compartments having a transparent top and a door in its side; a frame resting loosely in each section and removable through the door thereof, said 100 frame having notched cross bars at the top and bottom of each end thereof; grooved supporting bars in said chamber, the notched bars of said frames sliding in the grooves in said supporting bars; a plurality of glass 105 plates removably arranged in alternate sets

of notches, said plates being in substantially I-form; electric coils on said plates; insulating plates arranged in the notches between those containing the first mentioned 5 plates; electrodes on each of said frames connected with the corresponding coils; means for passing an electric current of high potential through said coils; and means at opposite ends of said chamber for passing

air successfully through said compartments, substantially as described.

In testimony whereof I have signed my name to this specification in the presence of two subscribing witnesses.

PAYTON J. H. MOORE.
